(57) **CLAIM**

The ornamental design for a utensil holder, as shown and described.

DESCRIPTION

FIG. 1 is a perspective view of a utensil holder showing a new design;

FIG. 2 is a top view of the utensil holder of FIG. 1;

FIG. 3 is a detail view of FIG. 2;

FIG. 4 is a front view of the utensil holder of FIG. 1;

FIG. 5 is a side view of the utensil holder of FIG. 1;

FIG. 6 is a bottom view of the utensil holder of FIG. 1;

FIG. 7 is a cross-sectional view taken along line 7-7 of FIG. 5;

FIG. 8 is a perspective view of another embodiment of the utensil holder of FIG. 1; and,

FIG. 9 is a cross-sectional view taken along line 9-9 of FIG. 8.

The components of the display shown in broken lines illustrate portions of the utensil holder form no part of the claimed design.
